UNITED STATES PATENT OFFICE.

BERNARD SIROTTA, OF NEW YORK, N. Y.

WOMAN'S DRESS.

1,214,601.

Specification of Letters Patent. Patented Feb. 6, 1917.

Application filed December 5, 1916. Serial No. 125,234.

To all whom it may concern:

Be it known that I, BERNARD SIROTTA, a citizen of the United States of America, and resident of New York city, in the county of 5 New York and State of New York, have invented certain new and useful Improvements in Women's Dresses, of which the following is a specification.

This invention relates to women's garments, such as skirts, dresses, coats or the like, the chief object being to provide a garment which will afford ample protection for the lower portion of the limbs of the wearer and at the same time permit of 15 freely engaging in sports and vigorous movements of all kinds without danger of deranging the garment.

As is well known, skirts and similar loose garments impede the movement of the 20 wearer when engaging in sports, for owing to their displacement or derangement they tend to interfere with the free movement of the lower limbs. This is particularly noticeable if the wearer is skating or participating in some similar vigorous sport, for the garment will lag or trail behind the body and will moreover present an ungainly appearance. This displacement of the garment is augmented by air disturbances and 25 the garment may become entangled with the legs of the wearer and thereby considerably impede the free movements which are essential to a complete enjoyment of the sport. Furthermore, any displacement of the garment in this manner tends to expose the 30 wearer to cold and, consequently, further detracts from the enjoyment of the sport.

According to this invention, the aforesaid objections are overcome by providing the 35 skirt portion of the garment with extensions or depending portions which are adapted to serve as gaiters or leggings to protect the legs of the wearer and which may at the same time afford a sure means of preventing 40 displacement or derangement of the garment. With such an arrangement the garment is forced to move with the lower limbs of the wearer and, consequently, cannot lag behind to present an ungainly appearance or become entangled with the legs 45 to impede the free movement of the wearer. The garment will in fact always hang in correct position and the wearer may move 50 without being hampered in any way.

55 Another advantage of the skirt resides in

that it cannot be blown by the wind away from its normal position.

In order that the said invention may be clearly understood and readily carried into effect, the same will now be described more 60 fully with reference to the accompanying drawings, in which:—

Figure 1 shows a skirt embodying the present invention. Fig. 2 shows a coat embodying the present invention. Fig. 3 is a 65 development of one of the leggings or gaiters of the garment shown in Fig. 1. Figs. 4 and 5 are partial views of a skirt showing two methods of attaching the leggings or gaiters thereto.

Referring particularly to Figs. 1 and 3, the skirt 1 is provided on either side with extensions or depending portions 2, which are adapted to form leggings or gaiters 3, 3 for each of the legs of the wearer. The extensions 2 may be formed of the same material as the skirt and they are extended and formed to shape, so that they may embrace the legs and instep and be fastened in position. In order to form the gaiters 3, the 70 75 extended portions 2 of the material of the skirt are cut to shape so as to provide wings or laterally extending portions 4 which may be passed freely around the legs of the wearer and secured in position by any suitable fastening devices. If desired, the material of the skirt at each side thereof may be extended downwardly to form an elongated strip 5 and the remainder of the gaiter may be formed of two or more strips 80 85 90 95

6, 7 which are suitably sewn thereto along the seam 8. The strip 6 may be sewn or otherwise secured at its upper end 8' to the lower edge 9 of the skirt while the other strip 7, secured to the strip 6 along the seam 100 105 110 115 120 125 130 135 140 145 or other garment would be cut to shape and the upper edge thereof would be appropriately secured to the skirt 1 so as to provide a wing or a free portion adapted to be 5 passed around the leg and instep of the wearer.

When the gaiters or leggings 3, 3 are not in use they may be turned up within the skirt or other garment as shown in broken 10 lines and secured out of sight by means of the securing devices 3'.

Fig. 2 shows a coat provided with the improved gaiters or leggings and in this arrangement the extensions 2 which form the 15 gaiters or leggings 3 are made from strips of material 16 which are laid on and sewn at 17 to the material of the coat. The strips of material 16 may serve to adorn the coat and provide a belt 18 partially extending 20 around the body of the wearer to secure the garment in position.

The extensions 2 forming the gaiters or leggings 3 are suitably shaped as in the arrangement last described and invisible fastening devices 19 are provided for the overlapping edges thereof.

If desired the gaiters or leggings 3 may be made independently of the skirt and attached thereto in any convenient manner as 30 shown in Figs. 4 and 5. In the former figure, the legging or gaiter 3 is attached to the skirt or other garment by being stitched thereto at 20, whereas in Fig. 5 the gaiter or legging is attached to the garment by means 35 of suitable securing devices 21, such as snap buttons or the like.

It will be readily seen that the gaiters or leggings 3 serve to retain the skirt or skirt portion of the garment in position and effectively prevent any displacement or derangement thereof during movements of the lower limbs of the wearer. The garment will al-

ways present a neat and tidy appearance and it will be prevented from hampering the movements of the wearer.

The invention may be applied to any woman's garment having a skirt portion and it should be understood that the term "skirt portion" is intended to cover a skirt *per se*, a dress, coat or any garment having a loose 50 portion embracing the lower limbs of the wearer.

What I claim is:—

1. The combination with a woman's garment, of gaiters comprising depending strips 55 extending from the bottom of the material of the garment, and located on either side thereof, laterally extending portions formed on said depending strips, and means for securing together the free ends of the depending strips and laterally extending portions.

2. The combination with a woman's garment, of gaiters comprising detachable depending strips extending from and below the material of the garment and located on either side thereof, laterally extending portions formed on said depending strips, and means for securing together the free ends of the depending strips and laterally extending portions.

3. The combination with a woman's garment, of gaiters comprising depending strips formed of the material of the garment and located on either side thereof, laterally extending portions formed on said depending strips, and means for securing together the free ends of the depending strips and laterally extending portions.

4. In a woman's garment having a skirt portion, the provision of gaiters extending from said skirt portion and means for securing said gaiters out of view when they are turned up under said skirt portion.

BERNARD SIROTTA.
